Primary Examiner — David G Muller*Assistant Examiner* — Nathan M Johnston(74) *Attorney, Agent, or Firm* — Lewis Roca Rothgerber Christie LLP(57) **CLAIM**

The ornamental design for an equipment holder, as shown and described.

DESCRIPTION

FIG. 1 is a perspective view of an exemplary embodiment of a design for an equipment holder showing my new design; FIG. 2 is another perspective view thereof; FIG. 3 is a left side elevation view thereof; FIG. 4 is a right side elevation view thereof; FIG. 5 is a top plan view thereof; FIG. 6 is a bottom plan view thereof; FIG. 7 is a front elevation view thereof; and FIG. 8 is a rear elevation view thereof.

FIG. 9 is a perspective view of a second embodiment of a design for an equipment holder; FIG. 10 is another perspective view thereof; FIG. 11 is a left side elevation view thereof; FIG. 12 is a right side elevation view thereof; FIG. 13 is a top plan view thereof; FIG. 14 is a bottom plan view thereof; FIG. 15 is a front elevation view thereof; and, FIG. 16 is a rear elevation view thereof.

The features shown in broken lines depict environmental subject matter only and form no part of the claimed design. The equipment holder is shown with a symbolic break in its length. The appearance of any portion of the article between the break lines forms no part of the claimed design.

1 Claim, 10 Drawing Sheets(56)
